UNITED STATES PATENT OFFICE.

HUBERT F. KRANTZ, OF BROOKLYN, NEW YORK, ASSIGNOR TO KRANTZ MANUFACTURING COMPANY, INC., OF BROOKLYN, NEW YORK, A CORPORATION OF NEW YORK.

SWITCHBOARD MECHANISM.

Application filed August 5, 1918. Serial No. 248,329.

To all whom it may concern:

Be it known that I, HUBERT F. KRANTZ, residing at Brooklyn, in the county of Kings and State of New York, have invented certain new and useful Improvements in a Switchboard Mechanism, of which the following is a specification.

This invention relates to a switch board mechanism.

10 An object of the invention is to provide an improved arrangement of parts adapted for use particularly in connection with heavy currents.

15 A further object is to provide an improved arrangement of parts whereby to afford substantial supporting means for the switch blades.

20 Other objects and aims of the invention, more or less specific than those referred to above, will be in part obvious and in part pointed out in the course of the following description of the elements, combinations, arrangements of parts and applications of principles, constituting the invention; and 25 the scope of protection contemplated will be indicated in the appended claims.

In the accompanying drawings which are to be taken as a part of this specification, and in which I have shown merely a preferred form of embodiment of the invention:

Fig. 1 is a diagrammatic plan view illustrating a device constructed in accordance with this invention.

35 Fig. 2 is a diagrammatic view showing in side elevation the structure disclosed in Fig. 1 and illustrating the same as including a casing or the like in which the parts may be contained.

40 Fig. 3 is a diagrammatic view showing in side elevation the structure disclosed in Fig. 1 and illustrating the same as it appears arranged for use in a dead face switch board.

45 Fig. 4 is a diagrammatic view somewhat similar to that shown in Fig. 1 illustrating a modification.

Fig. 5 is a diagrammatic view showing in side elevation the structure suggested in 50 Fig. 4.

Fig. 6 is a diagrammatic view similar to that shown in Fig. 3 but illustrating the type of switch mechanism shown in Figs. 4 and 5 and

Fig. 7 is a diagrammatic view similar to 55 that shown in Fig. 1 but illustrating a further modification.

Referring to the drawings for describing the structure which is illustrated therein, and referring first to the illustrations Figs. 60 1 and 2, the reference characters 1, 2 and 3 indicate the main line contacts, and the reference characters 4, 5 and 6 indicate the branch line contacts. The contacts 4, 5 and 6 are in alignment with and form pairs with 65 the contacts 1, 2 and 3 respectively as is a well known practice dealing with 3-wire systems. All of the contacts are preferably carried flat upon the face of a base plate as L, the main line contacts being suitably spaced 70 from the branch line contacts, and the pairs being properly spaced apart substantially as indicated.

Three switch blades as 7, 8 and 9 are provided for bridging the gap between the main 75 and branch line contacts. These switch blades are supported in a common carrier G, being insulated from each other and from the carrier by suitable insulation pieces 10. The carrier G is fixed to a U-shaped frame 80 11, the legs of which are spaced apart and are pivotally supported in a pair of brackets 12.

The brackets 12 are positioned in the spaces between the pairs of contacts, and the frame L bridges rigidly over the middle pair of contacts from one bracket to the other so that the three switch blades are provided with an unusually strong and substantial support. 90

A spring or the like, as 13, may be provided for urging the frame and switch blades away from the contacts.

The reference character H indicates an operating handle. It is pivotally supported, as at 14, in a suitable bracket carried preferably by the front wall as 16 of an enclosing casing 17, and is adapted to operate a toggle 18 in a manner fully shown and described in my copending application Serial 100 No. 42,956, filed July 31, 1915. Upward movement of the handle will straighten the toggle and swing the frame 11 to bring the opposite ends of the switch blades against the respective contacts, while downward 105 movement of the handle breaks the toggle and allows the spring 13 to snap the blades away from the contacts.

Suitable fuses or the like, as 19, may, of course, be provided in association with the branch line contacts.

In the modification Fig. 3 the parts are substantially as above shown and described except that the operating handle, as 20, is arranged at the front face of the base board 21 and is connected with the carrier G through the aperture 22 in the base board 10 by means of a link 23, this being the appropriate arrangement for providing a dead face switch board.

In the modification Figs. 4 and 5 the main line contacts are in the form of bus bars as 24, 25 and 26 spaced apart in substantially parallel relation and extending along one surface of a suitable base board 27. The switch blades as 28, 29 and 30 employed in this instance are similar to those shown and 20 described in my copending application above mentioned, that is, they are double ended and are pivotally mounted intermediate their ends, as at 31, for swinging their opposite ends into and out of engagement with the 25 bus bars and with juxtaposed separate branch line contacts 32, 33 and 34 which form pairs with the bus bars.

The switch blades are supported in a common carrier 35 and the supporting pivot 31 30 is provided between this carrier and a pair of independent supporting brackets 36 arranged one between the bus bars 24 and 25 and the other between the bus bars 25 and 26.

The supporting brackets 36 are fixed to 35 the base board 27 substantially mid-way between the bus bars and constitute a strong and substantial support for the carrier.

The operating handle, as 37 is similar to 40 what has already been described with reference to Figs. 1 and 2, the toggle being connected with the carrier 35, as at 39, so as to swing the switch blades against the bus bars and branch line contacts by straightening of the toggle.

45 Of course there may be any number of carriers and associated parts arranged spaced apart along the length of the bus bars.

In the modification Fig. 6 the structure is 50 the same in all respects as that described with reference to Figs. 4 and 5 except as to the position and manner of connecting and operating the toggle. In Fig. 6 the toggle is arranged to be operated by a link 40 which extends through an aperture 41 formed in a. 55 base board 42, the link being connected with a laterally extending arm 43 of an operating handle 44 at the front face of the board. This arrangement is adapted for use in connection with dead face switch boards.

60 In the modification Fig. 7, the structure is similar to that shown in Figs. 4 and 5. In this modification, however, the carrier is divided into sections 45, 46 and 47 each section being adapted to carry one of the blades 28, 65 29 and 30 respectively. The sections are in-

dependently mounted in suitable supports as 48, and 49 for the section 45, 50 and 51 for the section 46, and 52 and 53 for the section 47. The supports 49 and 50 are arranged between the bus bars 24 and 25 and 70 the supports 51 and 52 are arranged between the bus bars 25 and 26, while the supports 48 and 53 are arranged outside the bus bars 24 and 26 respectively.

The operating means for the sections 45, 75 46 and 47 may include toggles similar to that described with reference to Figs. 4 and 5, there being one disposed and connected between the sections 45 and 46, and another between the sections 46 and 47. Each of 80 these has an operating lever as 54 associated therewith, and these two levers are preferably connected by a hand grip member 55 by which they may be simultaneously operated to swing all of the sections and blades in 85 unison.

It will be apparent, from what has been shown and described, that the hand grip member for operating the structure Fig. 7 may be disposed for operation from either 90 side of a base board.

With switches, as herein shown and described, it will be possible and thoroughly practical to use switch blades and cooperative parts of unusually heavy construction. 95

As many changes could be made in this construction without departing from the scope of the invention as defined in the following claims, it is intended that all matter contained in the above description or shown 100 in the accompanying drawings, shall be interpreted as illustrative only and not in a limiting sense.

Having thus described my invention, what I claim as new and desire to secure by 105 Letters Patent is:—

1. A switch mechanism comprising three pairs of contacts spaced apart, three switch blades one for each pair of contacts, a carrier for said switch blades, means to operate the carrier to move the switch blades into "on" and "off" positions, and a pair of supports for said carrier disposed in the spaces between adjacent pairs of contacts and out of line therewith. 110

2. A switch mechanism comprising a plurality of pairs of contacts, said pairs being spaced apart, a plurality of switch blades one for each pair of contacts, a carrier for said switch blades, means to operate the carrier to move the switch blades into "on" and "off" positions, and supporting means for the carrier positioned between adjacent pairs of contacts and out of line therewith. 115

3. A switch mechanism comprising three bus bars spaced apart, three switch blades for deriving current from said bus bars, a carrier for said switch blades, means to operate the switch blades into "on" and "off" positions, and two separate supports for said 120 125 130

carrier arranged within the spaces between the adjacent bus bars and out of line therewith.

4. A switch mechanism comprising a base board, three bus bars supported at one face of said base board spaced apart in substantially parallel relation, three branch line contacts forming pairs with the bus bars respectively, three switch blades one for each 10 of said pairs, means to operate the switch blades to close connection between the bus bars and the respective branch line contacts, and two separate supports for the switch blades, said supports being arranged in the 15 spaces between adjacent pairs and out of line therewith.

5. A switch mechanism comprising three pairs of contacts spaced apart, three switch blades one for each pair of contacts, a carrier 20 for said switch blades, said carrier being made up of three sections one for each switch blade, means to operate the sections to move the switch blades into "on" and "off" positions, and a pair of supports for 25 said carrier disposed in the spaces between the pairs of contacts and out of line therewith and being connected with the carrier between the sections thereof.

6. A switch mechanism comprising three 30 pairs of contacts spaced apart, three switch blades one for each pair of contacts, a carrier for said switch blades, said carrier being made up of three sections one for each switch blade, a pair of supports for said 35 carrier disposed in the spaces between adjacent pairs of contacts and out of line therewith and being connected with the carrier

between the sections thereof, and operating means for the carrier comprising a pair of levers operatively connected with the carrier between the sections thereof, and a hand grip extending between and connected to said levers for simultaneously operating the switch blades. 40

7. A switch mechanism comprising a plurality of pairs of contacts, said pairs being spaced apart, a plurality of switch blades one for each pair of contacts, a carrier for said switch blades, said carrier being made up of sections one for each switch blade, 50 means to operate the carrier to move the switch blades into "on" and "off" positions, and supporting means for the carrier positioned between adjacent pairs and out of line therewith and engaging the carrier between the sections thereof. 55

8. A switch mechanism comprising three conductors arranged in parallel planes and having portions thereof separated to interrupt a circuit therethrough, a separate movable switch member for conductively connecting the portions of each conductor, a carrier for the said switch members adapted to move the said switch members to closed or open position and supports for the carrier 60 disposed in the space between the planes of the conductors and out of line therewith. 65

In testimony whereof I affix my signature in the presence of two witnesses.

HUBERT F. KRANTZ.
